UNITED STATES PATENT OFFICE

154,358

DESIGN FOR A CONFECTION VENDING
MACHINE

George Babcock, Chicago, Ill., assignor to Wm. Wrigley Jr. Company, a corporation of Delaware

Application July 25, 1946, Serial No. 131,920

Term of patent 14 years

(Cl. D52—3)

To all whom it may concern:

Be it known that I, George Babcock, a citizen of the United States, residing at Chicago, Cook County, Illinois, have invented a new, original, and ornamental Design for Confection Vending Machine, of which the following is a specification, reference being had to the accompanying drawing, forming a part thereof.

The dominant features of my design reside in the portion shown in full lines.

I claim:

The ornamental design for a confection vending machine, as shown and described.

GEORGE BABCOCK.
